UNITED STATES PATENT OFFICE.

IRVIN E. BARRICKLOW, OF ANTIOCH, CALIFORNIA.

FLUID-PRESSURE ENGINE.

No. 874,828.

Specification of Letters Patent.

Patented Dec. 24, 1907.

Application filed August 17, 1906. Serial No. 331,006.

To all whom it may concern:

Be it known that I, IRVIN E. BARRICKLOW, a citizen of the United States, residing at Antioch, in the county of Contra Costa and State of California, have invented new and useful Improvements in Fluid-Pressure Engines, of which the following is a specification.

This invention relates to an improved fluid pressure engine, and is particularly adapted to be driven by the combustion or explosion of fluid fuel and the direct pressure of the gas created thereby, although it may also be driven by steam pressure, the part of the engine used for the combustion of the fuel being in that case omitted.

The object of the invention is to provide a motor of this character which will be cheap in construction, occupy little space in proportion to the power generated, which on account of its simplicity of construction cannot easily get out of order, which can be worked at a high temperature without injurious results, and which can be readily reversed, even at full speed.

A further object of the invention is to provide an apparatus of this character which, although operated generally by means of gasolene or other fluid fuel, can be started like a steam engine by merely operating a valve or the like, and does not require to be given a number of revolutions by hand as in the ordinary gasolene motor.

Another object is to provide one in which the power shall be generated in the proportion as it is expended in doing the work.

In the accompanying drawings, Figure 1 is a longitudinal section, part being shown in side elevation, of my improved engine; Fig. 2 is an end view, part broken away; Fig. 3 is a detail broken side view of the pump; Fig. 4 is a detail broken side view of the sparking mechanism; Fig. 5 is a longitudinal section, part being shown in side elevation, of the explosion chamber; Fig. 6 is a longitudinal section of a modified form of said cylinder; Fig. 7 is a broken cross section of the explosion cylinder proper; Fig. 8 is a broken end view of the same; Fig. 9 is a broken plan view of the same.

In the accompanying drawing, 1 indicates a suitable base with a concave upper side 2 to which is bolted, as shown at 3, the shell 4 of the cylinder, having heads 5 bolted thereto, as shown at 6. Said base is hollow, as shown at 7, thus forming a reservoir to con-

tain the pressure fluid coming from the explosion chamber and from which it is supplied to the working cylinder.

The explosion chamber is arranged adjacent to the base, the cylindrical body 8 thereof being connected to said base by means of the heads 9, which are bolted to said body by the bolts 10 and also to the said base by the bolts 11. Each head of the explosion chamber has formed therein a conduit 12 leading from the interior of the explosion cylinder to the hollow base. Within said explosion chamber reciprocates a piston 13, which can abut alternately against hollow cylindrical valves 14 which slide in valve-ways 15 formed in the heads of the explosion chamber. Leading to said valves 14 are conduits 16 connected by pipes 17 with a common pipe 18 leading from a compressed air reservoir, not shown. Said conduits being opened in turn, compressed air is thereby admitted alternately to the opposite sides of the piston in the explosion chamber. At the same time the fluid fuel is carried with the compressed air into said chamber, and for this purpose with each conduit 16 is connected a small conduit 19 leading from the face of a boss 20 formed upon the head of the explosion chamber. Against said boss is bolted a T-shaped pump casing 21 having therein a pair of check valves 22, 23, both opening the same way, the check valve 22 permitting discharge into said small conduit 19, and the check valve 23 permitting discharge into said casing from a pipe 24. Both of said pipes 24 are connected with a common pipe 25 leading from the supply of oil or other fluid fuel.

The main or central portion of each T-shaped casing forms a pump cylinder, in which works a double ended plunger 26, one end working in each of said cylinders. The center of the plunger has secured thereto an arm 27 forked at its end to pass around a threaded spindle 28, screwed at its end into brackets or arms 29, depending from a yoke 30 hereinafter described. This yoke reciprocates with the piston in the explosion chamber, and thereby also the arms extending therefrom, and the spindle 28 secured to said arms, are reciprocated. On said spindle are adjustably secured nuts 31, on opposite sides of the forked end of the arm 27 leading from the pump plunger, so that, in the reciprocation of the yoke, said ends in turn abut against said arm, causing the

pump plunger to reciprocate. As the plunger reciprocates in each pump cylinder in its outward movement it opens a check valve 23 admitting oil into the pump casing, and 5 on its return movement the check valve 22 thereby causing the fluid fuel to be forced into the small conduit 19 leading to the conduit 16, where it is commingled with the compressed air, and is carried therewith into 10 the explosion chamber.

The spindle is retained in position in the arms 29 by means of nuts 32; also by screwing in or out the impact nuts 31, the length of stroke of the pump plunger can be increased 15 or diminished according to the character of the fluid fuel. Thus if gas is used, a much greater volume will be required and the pump plunger will be given a correspondingly greater length of stroke than when oil 20 is used.

As the pressure in front of the piston diminishes by reason of the outward passage of the exploded gases from the explosion chamber and from the working chamber, 25 the compressed air and the fluid fuel are forced by the pressure of the former into the explosion chamber causing the piston to advance to the opposite end of the explosion cylinder. It there abuts against the end of 30 the hollow cylindrical valve 14 at that end, to which valve is secured a spindle 33, which spindles extend inwards from the end of the yoke through stuffing-boxes 34, so that the yoke moves with the piston. This motion, 35 is communicated by means of said yoke to the hollow valve 14 at the rear end of the cylinder, which the piston has just left, causing said latter valve to advance and close the conduit 16 by which the compressed air and 40 fluid fuel were admitted to the cylinder, and it is arranged that immediately after said conduit is closed, an explosion is caused by a spark, this spark being produced in the following manner. Upon the yoke 30 is 45 secured by a set screw 36 a sleeve 37 having ears 38 between which is pivoted a contact block 39 having a sharp edge 40 and a square back 41, against which presses a flat spring 42. Said edge is adapted to contact 50 with a contact plate 43 secured upon an arm 44 extending from the casing of the cylinder and insulated therefrom, as shown at 45. In the movement of the yoke said pivoted block is swung in contact with the plate and 55 against the pressure of the spring, until it is released from contact with said plate, whereby the spring, bearing upon the square back of the contact block snaps it to its normal position thus making the quick movement 60 necessary for sparking. The contact plate and block are connected with the two parts of the sparking plug 46 in the interior of the cylinder, the insulated contact plate being connected by an insulated wire with the 65 insulated part of the spark plug and the

block and the other part of the plug by the metal part of the machinery. Thus a spark is produced as soon as the passage for the compressed air and gas has been closed.

The first result of the explosion is to cause 70 the piston to advance still farther in the same direction, driving with it the cylindrical valve 14 at that end, thus forcing out all waste gases remaining in the head of the explosion chamber. Since the two valves 14 75 move in unison the valve at the other end is moved inwards in the same direction, until at the rear of said other valve the passage 12 is opened in the other head of the explosion chamber, leading to the hollow base or reservoir 80 and thence to the working cylinder. The products of combustion are thus forced with great pressure into said reservoir, maintaining the supply of pressure fluid therein. From said hollow base or reservoir the gases 85 pass by an opening 47 into an annular chamber 48 in said latter chamber. Said opening is controlled by a piston valve 49 operated by a forked lever 50 attached to a collar 51 loose on the shaft 52, to the opposite sides of 90 which are attached arms 53 of bell-cranks 54, the other arms of which carry governor balls 55, said arms being pivoted at 56 on an extension 57 from a collar 58 secured upon said shaft. By this means the opening is more or 95 less closed by said piston valve according to the speed of revolution of the shaft. Said shaft carries a runner 60 near the face of which are secured a circular series of vanes 61. Said vanes are connected at each end 100 to a ring 62, each ring having radial grooves 63 to receive the ends of the vanes, and also having at the bottom of each groove a hole 64 to receive stud 65 extending from the end of the vane, said stud being then riveted in 105 the outside of the ring. One of the rings is then screwed or otherwise secured to the runner near its outer edge. However, this construction is not essential as the vanes may be made in one piece with the runner, if desired. 110 The inner edges of said vanes extend close to the outer wall of a ring 66, on which are arranged two series of impact passages 67, said passages of the two series being forked obliquely, but in opposite directions, and 115 against the inner wall of said ring 66 is a reversing ring 68, having passages 69 adapted to register with one or the other of the series of passages in the ring 66. Said inner ring is required to be shifted only a short distance 120 to change the connection from one series of passages to the other, and this is accomplished by means of an arm 70 on the lower end of a spindle 71 extending through a stuffing box 72, and carrying on its outer end a reversing handle 73. By moving said handle said spindle can be turned so as to throw the piston sufficiently to move the reversing ring so that the passages therein connect with one series of passages on the outer ring in 125 130

stead of with the other. Said passages may be either narrow slits or a line of holes, the latter being preferred for cheapness. The pressure fluid emerging therefrom impinges 5 against the concave sides of the vanes, impelling the runner forwards, and expanding largely in so doing. The pressure fluid, after doing its work, passes from the vanes into an exhaust chamber 74 from which it escapes by 10 a passage 75.

In the modification shown in Figs. 6 to 9, inclusive, compressed air and fluid fuel are supplied by central passages 76 and 77 to the interior of a cylindrical casing 78 forming a 15 jacket around the explosion chamber, spaced therefrom to permit the compressed air to pass around the cylinder. Said compressed air passes through openings 79 formed in the heads of the explosion cylinder into the interior of said cylinder in the same manner as 20 before, and carries with it the fluid fuel. If oil is used, the oil is allowed to drop onto the top of the explosion cylinder, and in order to gasify the oil it is caused to flow over the 25 surface of said cylinder in a tortuous path by means of walls or ribs 80 formed upon the outer surface of said cylinder and extending zigzag, or alternately, from the flanged heads thereof. The oil in passing along said tortuous path to the two sides of the cylinder is 30 gasified, the gas therefrom being mixed with the compressed air, and any tarry or other residue of the oil is collected in a chamber 81 at the bottom, from which it can be drawn 35 off from time to time by a pipe 82. This jacket can readily be removed when it is desired to clean the exterior of the explosion chamber.

I claim:

40 1. A fluid pressure engine, comprising a generator cylinder, a piston reciprocating therein, an impact cylinder, a runner therein adapted to be revolved by fluid pressure, a conduit between the two cylinders, a conduit 45 leading to the generator cylinder for supplying the compressed air and fluid fuel thereto, and a pump operated in unison with the piston for supplying the fuel to said conduit, substantially as described.

50 2. A fluid pressure engine, comprising a generator cylinder, a piston reciprocating therein, an impact cylinder, a runner therein adapted to be revolved by fluid pressure, a conduit between the two cylinders, a conduit 55 leading to the generator cylinder for supplying the compressed air and fluid fuel thereto, a pump operated in unison with the piston for supplying the fuel to said conduit, and means also operated in unison with the piston 60 for igniting said fuel, substantially as described.

3. A fluid pressure engine comprising a generator cylinder, a piston reciprocating therein, an impact cylinder, a runner therein 65 adapted to be revolved by the fluid pressure,

a conduit leading to the latter cylinder from each end of the former, means for supplying compressed air to each end of the generator cylinder, a conduit for fuel leading to each end of the generator cylinder, means, operated in unison with the piston, for igniting 70 said fuel, and means for simultaneously closing the compressed air inlet and opening the conduit to the impact cylinder at either end of the cylinder, and for opening said inlet and closing said conduit at the other end, substantially as described.

4. A fluid pressure engine comprising a generator chamber having a valve seat at each end, a hollow valve sliding in each seat, 80 a yoke connecting said valves whereby they move in unison, and a piston reciprocating in said cylinder and adapted to abut against each valve alternately, substantially as described.

5. A fluid pressure engine comprising a generator cylinder having a valve seat at each end, a valve at each end for controlling the inlet and outlet to said end, a yoke connecting the two valves whereby they move 90 in unison, and a piston reciprocating in the cylinder and adapted to abut against said valves alternately, substantially as described.

6. A fluid pressure engine comprising a generator cylinder having a valve seat at 95 each end, a valve at each end for controlling the inlet and outlet to said end, a yoke connecting the two valves whereby they move in unison, a piston reciprocating in the cylinder and adapted to abut against said valves 100 alternately, a pipe for conducting the fluid fuel alternately to each end of the cylinder, a pump for pumping the fuel to the cylinder, and an operative connection between said pump and yoke whereby said pump can be 105 operated by the movement of the yoke caused by the impact of the piston on the valves, substantially as described.

7. A fluid pressure engine comprising a generator cylinder having a valve seat at 110 each end, a valve at each end for controlling the inlet and outlet to said end, a yoke connecting the two valves whereby they move in unison, a piston reciprocating in the cylinder and adapted to abut against said valves 115 alternately, a pipe for conducting the fluid fuel alternately to each end of the cylinder, a pump for pumping the fuel to the cylinder, an operative connection between said pump and yoke whereby said yoke can be operated 120 by the movement of the yoke caused by the impact of the piston on the valves, and means for adjusting said operative connection to vary the stroke of the pump, substantially as described.

8. A fluid pressure engine, comprising an explosion chamber, an impact chamber, a runner therein, a conduit leading from the first chamber to the second, means for supplying explosive gases to said explosion 130

chamber and exploding them therein, a jacket around said generator cylinder, and means for causing the pressure fluid and compressed air to pass between said cylinder and jacket before entering the cylinder, to be heated thereby, substantially as described.

9. A fluid pressure engine, comprising an explosion chamber, an impact chamber, a runner therein, a conduit leading from the 10 first chamber to the second, means for supplying explosive gases to said explosion chamber and exploding them therein, a jacket around said generator cylinder, and

means for causing the pressure fluid and compressed air to pass into a tortuous path 15 between said cylinder and jacket before entering the cylinder, to be heated thereby, substantially as described.

In testimony whereof I have hereunto set my hand in the presence of two subscribing 20 witnesses.

I. E. BARRICKLOW.
